UNITED STATES PATENT OFFICE.

OLIVER P. UNDERWOOD, OF INDIANOLA, IOWA.

MECHANICAL MOVEMENT.

1,139,450.

Specification of Letters Patent. Patented May 11, 1915.

Application filed February 8, 1910. Serial No. 542,781.

To all whom it may concern:

Be it known that I, OLIVER P. UNDERWOOD, a citizen of the United States, residing at Indianola, in the county of Warren 5 and State of Iowa, have invented a certain new and useful Mechanical Movement, of which the following is a specification.

My invention relates to that class of mechanical movements adapted for use in engines in which a number of cylinders are arranged in parallel planes in a circle and all of them have their pistons connected to a universal shaft located concentrically relative to the cylinders and which are so arranged as to successively give to the shaft a rotary impulse through a part of the revolution of the shaft.

My object is to provide in a device of this class simple and durable means for transmitting the longitudinal motion of the pistons to a rotary motion as applied to the crank wheel in such a manner that all of the pistons may be operated successively and each will impart to the crank wheel its 25 maximum energy.

The figure shows a central, longitudinal, sectional view through a complete engine embodying my invention.

Referring to the accompanying drawings, 30 I have used the reference numeral 10 to indicate the engine casing. Mounted in one end of the engine casing is a short power shaft 11 having a fly wheel 12 fixed thereto, and on the other end of the power shaft 35 is a crank wheel 13. At the opposite end of the casing is a series of engine cylinders 14 arranged parallel with each other and in a circle, the center of said group of engine cylinders being in line with the center 40 of the power shaft. Surrounding all of said cylinders is a water jacket 15 for cooling purposes. Contained within the central space between the engine cylinders is a cylinder 16 to receive the engine valve operating 45 mechanism. Mounted within this cylinder 16 is a rotary engine shaft 17 having a crank wheel 18 at one end. Mounted at the end of the cylinder 16 nearest the engine shaft 50 is a cross head 19 curved at its central portion in a direction toward the power shaft and having at its center a substantially spherical bearing member 20 which extends in a direction away from the power shaft.

For operating the crank wheel 13, I have 5 provided an operating shaft 21 having one end rotatably mounted in the crank wheel

and having at its other end a bearing socket 23 to receive the spherical bearing member 20. Beyond the said bearing member, the shaft is provided with an extension 24 having a ball 25 thereon extended into a socket formed in the crank wheel 18.

Mounted within each of the cylinders is a piston 26 of ordinary construction and having arranged therein two guide-ways 27 at opposite sides thereof, said guide-ways being arranged radially relative to the longitudinal center of the entire engine. In each of said guide-ways is a cross head 28 radially slidable with relation to the longitudinal axis of the engine and provided with a socket 29. In each of the sockets 29 is a ball 30 and each ball is provided with a rigid arm 31 curved in a direction, first away from the longitudinal center of the engine, and then toward the longitudinal center of the engine, and its other end is connected to the operating shaft 21.

In the practical operation of this portion of the engine and assuming that the piston 30 shown at the top of the figure is moved in a direction toward the fly wheel 12, this movement will impart to the outer end of the operating shaft 21 a segmental movement which will turn the crank wheel 13 a part 85 revolution; then as the outer end of the shaft 21 moves to the position shown by dotted lines in the figure, the cross head 28 will move outwardly relative to the longitudinal center of the engine as also illustrated by dotted lines. Each of the other arms 31 and the corresponding pistons 26 will have the same movement imparted to them successively, and by this arrangement and assuming that the pistons were successively moved, the outer end of the shaft 21 will be given a circular movement which will carry with it the crank wheel 13 and the power shaft, and on account of the simple arrangement of the parts friction will 90 be reduced to a minimum. The shaft 17 will also be rotated in unison with the shaft 11 by means of the extension 24 and the crank wheel 18.

I claim as my invention:

In a device of the class described, a support, a power shaft mounted thereon, a crank mounted on said power shaft, an operating shaft operatively connected with said crank, and having one end universally movable about the line of the longitudinal axis of said power shaft, a plurality of arms

105

110

secured to said operating shaft, a plurality of members mounted on said support, a member radially slidably within each of said plurality of members, means for operatively connecting each of said arms with one of said sliding members to permit sliding motion of the arms with relation to said fixed members on radial lines around the line of the longitudinal axis of the power shaft, and

also arranged to permit radial pivotal movement of said arms with relation to said sliding members.

Des Moines, Iowa, Dec. 15, 1909.

OLIVER P. UNDERWOOD.
